UNITED STATES PATENT OFFICE.

FREDERICK DUDLEY LEMAN, OF RATON, NEW MEXICO.

RAILROAD TIE.

Application filed March 16, 1925. Serial No. 15,940.

To all whom it may concern:

Be it known that I, FREDERICK DUDLEY LEMAN, a citizen of the United States, and a resident of Raton, in the county of Colfax and State of New Mexico, have invented certain new and useful Improvements in Railroad Ties, of which the following is a specification.

This invention relates to railroad ties and has for an important object the provision of simple means whereby the rails may be adjusted thereon for straightening the track either when the track is originally laid or at any time thereafter.

15 A further aim of the invention is to provide a railroad tie which is durable, easy to lay and cheap to manufacture.

Other objects and advantages will be apparent during the course of the following 20 description.

In the accompanying drawing forming a part of this application and in which like numerals are employed to designate like parts throughout the same,

25 Figure 1 is a plan view of the improved rail tie in use.

Figure 2 is a side elevation of the improved rail tie in use, parts being shown in section.

30 Figure 3 is a group perspective of the rail engaging rods or hooks and the means for holding the hooks in position.

Figure 4 is a detail view illustrating a slight modification of the invention.

35 In the drawing wherein for the purpose of illustration is shown a preferred embodiment of the invention, the numeral 5 designates the body of the improved tie. The body may be made of cement, glass, burnt clay or any other material found suitable for the purpose. By making the tie body of cement or the like the same is rendered impervious to water and the need of treating the tie with creosote or other water-proofing agent as is now done is overcome.

Figure 2 illustrates that a pair of metallic top plates 6 are arranged on the upper surface of the body 5 and are overlapped and joined as indicated at 7. The longitudinal side edges of the top plates 6 are provided with depending flanges 8 which contact with the sides of the body 5 and thereby hold the top plates in position. It might be said that the top plates 6 form a slidable

unit on the upper surface of the body 5 as 55 the top plates are securely and permanently connected as shown at 7.

The drawing illustrates that the top plate or unit is provided adjacent the ends thereof with spacing elements 10 upon which the rails 11 are mounted. The rails are securely and positively secured to the slidable top plate by clamping devices 14 secured to the top plate and to the spacing elements 10 by bolts 15 or other suitable fastening devices.

It is thus seen that the rails are securely connected to the top plate without the aid of spikes or the like which would embed themselves in the tie. The rails are held in 70 position by a plurality of bars or rods 16 and 18, the rods 16 being somewhat shorter than the rods 18 and being provided at their inner ends with hooks 20 to engage the base flanges of the rail. The outer ends 75 of the hooks 16 and 18 are provided with nuts 22 by means of which the rods may be tightened or loosened as the occasion requires.

Figure 2 illustrates that the inner ends of 80 the rods 18 are provided with hooks or bills 24 which cooperate with the bills 20 in engaging the rails and holding the same firmly in position. The sets of rods 16 and 18 arranged at opposite sides of the body 5 85 are extended through end plates 26 flatly engaged with the ends of the body 5. It will be seen that by an adjustment of nuts 22 on the rods 16 and 18 the rails 11 and consequently the top plate on the body 5 90 may be adjusted. This arrangement permits the rails to be quickly straightened without changing the position of the body 5. Thus the body 5 may remain undisturbed in the road bed.

95 The intermediate portions of the rods 18 are extended through the ears or rolled portions 30 of U-shaped bands 32 which embrace the body 5. The sides of the U-shaped bands 32 are extended above the top plate 100 6 and are apertured for the reception of connecting bolts 37 by means of which the arms are firmly held in position. Also, the rods 18 act as a means to hold the bands 32 in position as the rods must extend downwardly into a bowed position to engage the ears or rolled portions 30. The bands 32 are received in recessed portions 40 in the

body and are held against longitudinal movement on the body by contact with the walls of the recesses.

Particular attention is directed to the fact that the body 5 consists of three short separately constructed sections arranged in end-to-end relation and provided at their meeting ends with L-shaped spacing elements 44. In other words the body 5 consists of a central section and two end sections, all of which are in alignment and are spaced by the L-shaped elements 44. The bands 32 overlap the ends of the sections of the tie and thereby hold the tie sections in alignment. The bands 32 also hold the chafing plates 44 in position.

Figure 2 illustrates that metallic base plates 48 have their ends confined between the bands 32 and the body 5. The inwardly extending portions 49 of the end plates 26 extend beneath and hold the adjacent portions of the base plates 48 in position.

With reference to the foregoing description taken in connection with the accompanying drawing it will be apparent that a rail tie constructed in accordance with this invention is provided with simple means to hold the rails in position and to vary the position of the rails for the purpose of straightening the track.

In the modified form of the invention illustrated in Figure 4 the rods 16 and 18 may be provided between the end plates 26 and the nuts 22 with springs 60 by means of which a limited yielding movement of the rails is permitted.

Having thus described the invention, what is claimed as new is:

1. A rail tie comprising a body, a top plate movably positioned on the body and having side flanges contacting with the body, means for clamping rails on said top plate, fastening rods arranged at opposite sides of said body and having hooks engaged with the rails, and end plates receiv-

ing said rods and engaged with the ends of the body.

2. A rail tie comprising a body, a top plate movably positioned on the body and having side flanges contacting with the body, means for clamping rails on said top plate, fastening rods arranged at opposite sides of said body and having hooks engaged with the rails, end plates having connection with said rods, and bands extended about the body of said tie and having ears receiving certain of said rods, said body being provided with recesses receiving said bands to hold the bands against longitudinal movement.

3. The construction set forth in claim 2, said body consisting of a plurality of separate sections arranged in end-to-end relation and having their meeting ends overlapped by said bands.

4. A rail tie comprising a body, a top plate movably positioned on the body, means for clamping rails to said top plate, fastening rods arranged at opposite sides of said body and having hooks to engage said rails, end plates having openings receiving said rods, means on said rods for adjusting the same, bands of U-shaped formation embracing said body and having ears receiving certain of said rods, said body consisting of a plurality of separate sections, the meeting portions of which are embraced by and are overlapped by said bands, and a base plate arranged beneath said body.

5. The construction set forth in claim 4, said end plates being provided with inwardly extending portions underlying and engaging said base plates.

6. A rail tie comprising a body, end plates engaged with the body, rail engaging hooks extended through the end plates and having nuts, and springs confined between the nuts and the end plates.

FREDERICK DUDLEY LEMAN.
